F. J. PLYM

WINDOW CONSTRUCTION

Filed Jan. 14, 1926

Inventor:
Francis J. Plym.
Wallace R. Lane.
M. H. S.

UNITED STATES PATENT OFFICE.

FRANCIS J. PLYM, OF NILES, MICHIGAN, ASSIGNOR TO THE KAWNEER COMPANY, OF NILES, MICHIGAN, A CORPORATION OF MICHIGAN.

WINDOW CONSTRUCTION.

Application filed January 14, 1926. Serial No. 81,149.

The present invention relates to a new window construction in which the upper sash and two lower sashes open outwardly, and among the objects of my invention are 5 the following:

To provide a window construction in which the upper sash is so formed as to open downwardly and outwardly, being hinged on a movable horizontal axis, and the two 10 lower sashes open outwardly but are hinged on vertical axes.

To afford a window construction in which the upper sash is constructed to slide downwardly when opening outwardly so as to 15 leave a space for ventilation above the top of the sash.

To provide a slot member in a window construction in which a pin attached to the upper sash member may slide.

20 To afford a window construction in which the upper sash has means at the sides thereof to protect against inclement weather when the upper sash is open.

A further object is to provide a combination in which the upper sash may be an awning or opaque glass such as the visor 25 of an automobile having a flexible side member for protection against inclement weather, together with outwardly opening windows 30 in the bottom sash and such other objects, advantages and capabilities as will be later more fully appear.

My invention further resides in the combination, construction and arrangement of 35 parts illustrated in the accompanying drawing, and while I have shown therein a preferred embodiment of my invention I wish it understood that the same is susceptible of modification and change without departing 40 from the spirit of my invention.

Referring to the drawings, Fig. 1 is a perspective view of my improved window construction.

Fig. 2 is a fragmentary perspective view 45 of the upper corner of the window showing the upper sash open.

Fig. 3 is a fragmentary vertical sectional view of the upper portion of my improved window, and;

50 Fig. 4 is a fragmentary elevational view of an upper corner of my window looking from the inside.

My invention more in detail comprises an upper sash 1 carrying a corner bracket 2.

A flange 3 of this corner bracket 2 is slidably attached to a hollow plate 4 which is secured to the side of the window frame 5 by lugs 5^a and rivets, bolts or the like. This plate 4 has a slot 6 in which slides a pin 7 having a head 8. It will be clearly seen that as the sash 1 is opened the pin 7 slides downwardly in the slot 6 so as to leave a space 9 for ventilation above the top of the sash 1. Simultaneously with the downward movement of the upper edge of sash 1, the body 60 of the sash swings outwardly by virtue of its pivotal connection with the outer end of each of the links 10, the inner ends of which are pivotally connected to the window frame. 65

The upper sash 1 is provided with flexible 70 members 11 covering the sides in order to protect against inclement weather. It will be seen that these flexible members provided on each side of the upper sash when opened will prevent rain, wind, snow or the like 75 from blowing in the room and due to their flexible nature will readily fold up when the window is closed. A transverse bar 12 separates the upper and lower sashes. Each 80 of lower sashes 13 and 14 is pivoted on a vertical axis and swings outwardly from either side of the window.

It will be readily seen that my new window construction involves simplicity and ease of installation. There are no complicated parts to get out of repair and any parts may be easily replaced or repaired. It may be used as a window solely or in combination with an awning in the upper sash. 85

Having now described my invention, I 90 claim:

1. A window construction comprising a downwardly moving and outwardly opening upper sash, a corner bracket attached to said sash, a plate secured to the window 95 frame adjacent to said bracket, and having a slot, a pin attached to said corner bracket slidable into said slot, and a pair of outwardly opening lower sashes.

2. A window construction comprising a sash having a corner bracket, a plate secured to the window frame adjacent to said bracket and having a slot, a pin attached to said corner bracket and slidable in said slot whereby said sash may move downwardly and leave 100 a space above the sash for ventilation and open outwardly, and a flexible member attached to the sides of said sash. 105

3. A window construction comprising a sash hinged on a vertical axis, a corner bracket attached to said sash, a plate adjacent to said bracket having a slot, a pin attached to said corner bracket and slideable in said slot for lowering said sash, a pair of links for opening said sash outwardly as it is lowered and a flexible member attached to the sides of said sash.
- 10 4. In a window construction, a sash provided with a corner bracket having a flange, a window frame having a plate provided with a slot, a pin attached to said corner bracket and slideable in said slot, and a pair of links each pivoted at one end to the sash and at the other end to the window frame so that as the sash is swung outwardly its upper end will simultaneously move downwardly a limited distance.
- 15 5. In a window construction comprising a sash adapted to be used as an awning and having a corner bracket adapted to slide in an adjacent slotted plate for moving said sash downwardly and outwardly and weather protecting side pieces on said sash.
- 20 6. A window construction comprising an upper sash, a corner bracket attached to said sash, a plate secured to the window frame adjacent said bracket and having a slot, a pin attached to said bracket and slideable in said slot for moving said sash downwardly, links for moving said sash outwardly, a flexible member on the sides of said upper sash and a pair of outwardly opening lower sashes separated from said upper sash by a transverse bar.
- 25 7. Window construction comprising a window frame, a pair of outwardly opening sash pivotally mounted in the lower portion of the frame, an upper sash in said frame, a hollow slotted plate secured to said frame at each side of the upper sash, the slot of each bracket being arranged at an angle to the vertical, a bracket on the upper sash at each corner and each having a pin slideable in said slot, a pair of links each pivoted at one end to the upper sash and at the other end to the window frame, so that as the
- 30 upper sash is swung outwardly its upper edge will simultaneously move downwardly, and a flexible weather shield covering the space between the side edges of the upper sash and window frame when the upper sash is in open position.
- 35 8. A window construction comprising a downwardly moving and outwardly opening upper sash, a bracket on said upper sash, a slotted plate secured to the side of the window frame and adapted to engage the bracket, and a pair of outwardly opening lower sashes.
- 40 9. A window construction comprising a downwardly moving and outwardly opening upper sash, a bracket on said upper sash provided with a pin, a slotted plate secured to the side of the window frame and adapted to receive the pin, and a pair of outwardly opening lower sashes.
- 45 10. A window construction comprising a downwardly moving and outwardly opening upper sash, means for securing such sash upon a horizontal axis, said means comprising a bracket member secured to the sash and a slotted plate secured to the side of the window frame, and a pair of outwardly opening lower sashes.
- 50 11. A window construction comprising a downwardly moving and outwardly opening upper sash, means for securing said sash upon a horizontal axis, said means comprising a bracket member mounted on the edge of said sash and a slotted plate secured to the side of the window frame.
- 55 12. A window construction comprising a downwardly moving and outwardly opening upper sash, means for adjustably securing said sash upon a horizontal axis, said means comprising a bracket member secured to the sash and a slotted plate secured to the side of the window frame, and a flexible member secured to the side of the sash and the window frame.
- 60 In witness whereof, I hereunto subscribe my name to this specification.

FRANCIS J. PLYM.
